United States Patent

Des. 235,878
Patented July 15, 1975

235,878

MULTI-STUD TERMINAL

Charles W. Candiotti, Garden City, N.Y., assignor to
Minnesota Mining and Manufacturing Company, St.
Paul, Minn.

Filed Oct. 10, 1973, Ser. No. 404,914

Term of patent 14 years

Int. CL D13—03

U.S. CL. D26—1 A

FIG. 1

FIG. 2

FIG. 3

FIG. 4

FIG. 5

FIG. 6

FIG. 1 is a top perspective view of a multi-stud terminal showing my new design.

FIG. 2 is a top plan view thereof.

FIG. 3 is a bottom plan view thereof.

FIG. 4 is a side elevational view thereof, opposite side elevational views being identical but of opposite hand.

FIG. 5 is an end view as taken from the right-hand end of FIG. 2.

FIG. 6 is an end view as taken from the left-hand end of FIG. 2.

I claim:

The ornamental design for a multi-stud terminal, as shown and described.
